J. DUNLOP,
WINDOW SHADE.
APPLICATION FILED OCT. 26, 1918.

1,307,729.

Patented June 24, 1919.

Judson Dunlop,
BY
J. W. Parker
ATTORNEY

UNITED STATES PATENT OFFICE.

JUDSON DUNLOP, OF FLORAL PARK, NEW YORK, ASSIGNOR OF ONE-HALF TO WALTER S. BARNES, OF NEW YORK, N. Y.

WINDOW-SHADE.

1,307,729.

Specification of Letters Patent. Patented June 24, 1919.

Application filed October 26, 1918. Serial No. 259,750.

To all whom it may concern:

Be it known that I, JUDSON DUNLOP, a citizen of the United States, and resident of Floral Park, in the county of Nassau and State of New York, have invented certain new and useful Improvements in Window-Shades, of which the following is a specification.

This invention relates to window shades, and my improvements refer particularly to the novel construction and arrangement of a window shade relatively to the window it serves whereby either or both the lower and upper portions of the window may be exposed or obscured, to any desired degree.

Briefly expressed, my invention comprises the employment of an ordinary spring roller having attached thereto a shade longer than the length of the window. This spring roller is revolvably mounted in bearings located at the window sides about midway the length of the window, and a plain roller is engaged with the shade above the spring roller, so that the shade passes from the spring roller, up over the plain roller, and thence downwardly, below the spring roller, to cover the lower portion of the window. The plain roller is mounted in bearings which are slidable upon fixed guides located at the sides of the window, and slidable pulley means are provided whereby cords engaged with said plain roller may draw it upwardly, against the tension of the spring roller, for purposes of covering more or less the upper portion of the window.

The lower end of the shade has means which frictionally engage the guides to hold the shade in an adjusted position, these frictional means being releasable to permit the shade to be drawn downwardly against the tension of the spring roller, or to allow said shade to draw up under said spring tension.

Other features and advantages of my said invention will hereinafter appear.

45 In the drawing:

Figure 1 is a view, from the interior, of a window equipped with my improved shade.

Fig. 2 is a side view thereof, on an enlarged scale, and

50 Fig. 3 is a further enlarged detailed view

of a lower corner portion of the window frame and shade.

My invention comprises the use of an ordinary spring roller 1, having attached thereto, in the usual manner, a shade 2. The 55 spring roller 1, instead of being mounted at the upper end of the window, as is usual, is mounted in brackets or bearings 3-3, which may be secured about centrally of the window length or height, respectively at the 60 opposite sides of the window frame 4. Rigidly mounted at the respective sides of the window frame are guide rods 5, as by the upper and lower brackets 6, and a plain roller 7, revolvable in hangers 8, 8^a, is by said 65 hangers loosely engaged with the rods 5, and slidable vertically thereon. The roller 7, which is located above the roller 1, is engaged under the shade 2, which latter wraps over said roller 7 and extends downwardly, preferably behind the roller 1, to a point below said roller 1, where said shade is provided with a lower stiffened terminal portion. The stiffening may comprise a 70 board 9 suitably secured to the lower end of 75 the shade.

The hanger 8 at one side of the window is engaged with a cord 10 that passes over an upper pulley 11, said cord extending from said pulley, across the top of the window, 80 and over a pulley 12 at the opposite upper side of the window, said cord 10 thence extending downwardly to a lower sheave engaging device 13.

The pulley 12 is a twin pulley, to accommodate in one groove the cord 10, and in the other groove a second cord 14, that branches from cord 10, and connects with the hanger 8^a. Hence the upward fold of the shade may, through the medium of roller 90 7 and cords 10, 14, be drawn upwardly to cover the upper portion of the window, or a part thereof, from the center up, against the tension of the spring roller 1. As will be apparent the shade operation with respect 95 to the upper portion of the window, is accomplished irrespective of any movement of the lower portion of the shade, which latter may be drawn up by the spring roller so that its terminal portion lies closely under the 100

roller 1, to thus expose the entire lower half of the window, or which may be drawn by hand, against the tension of the spring roller, down to any desired lower position, 5 to cover either a part or the whole of the lower half of the window.

Anchorage means are necessary for the lower shade portion, to hold it against displacement when the upper portion is being 10 raised by the roller 7. Therefore I provide frictional devices which may be in the form of L-shaped plates 15, secured at the opposite ends of stiffening member 9, and having vertical slots 16, to receive, respectively, 15 the guide rods 5. Under tension of the spring roller these slots 16, at their rear, upper, and forward, outer edges, bind with frictional purchase against the guide rods, and thus retain the shade in a desired set 20 position. But, by canting forwardly the plates 15, as through the medium of a lug or handle 17, carried by the stiff terminal portion of the shade, this frictional binding engagement can be released, so that the plates 15, 25 then held with their slots free upon the guide rods, may with the shade be moved up or down.

Hence, the upper and lower portions of the shade are adjustable independently of 30 each other, but it is a condition of the operation of the upper portion that the lower portion be anchored.

The cord 10, which operates the upper shade portion, freely engages the sheave 13, 35 which latter is journaled in a bracket 18; and said cord may be frictionally caught between the sheave and bracket to thus restrain the said upper shade portion against the winding up action of the spring roller,—said 40 cord being released when it is desired to operate said upper shade portion.

A spring cushion is provided, as in the form of the helical springs 19, 19, mounted on the guide rods 5, just above the position 45 occupied by the spring roller 1, said springs 19, 19, being adapted to receive the impact of the hangers 8, 8^a, in case the cord 10 should be let loose against the shade winding action of the spring roller, in which 50 event the hangers and roller 7 would be retracted suddenly toward roller 1.

Variations may be resorted to within the spirit and scope of my said invention, and parts thereof used without others.

55 I claim:

1. An improved window shade having a spring roller, bearings therefor fixed intermediate the top and bottom of the window served, a shade carried by said roller, and 60 means for moving an upper portion of said shade above said roller, while permitting the lower portion of said shade to be moved below said roller, whereby the upper and lower

portions of the window may independently be partially or wholly obscured or exposed. 65

2. In an improved window shade, in combination, a spring roller carrying a shade, means for mounting said roller upon a window frame, means for anchoring the lower end of said shade, and means for moving 70 upper portions only of said shade relatively to said roller to cover or expose the window above the location of said roller.

3. In an improved window shade, in combination, a spring roller, carrying a shade, a 75 window frame, means for mounting said roller in a fixed position intermediate the top and bottom of the window frame, vertical guide means at the sides of the said window frame, a plain roller slidably engaged 80 with said guide means and located above said spring roller, whereby the shade may pass over said plain roller and depend below said spring roller, means for anchoring said shade at its lower end, and means for moving 85 said plain roller vertically with the upper portion of said shade.

4. In an improved window shade, in combination, a spring roller, a shade upon said roller having a stiff, terminal portion, means 90 for moving upper portions of said shade relatively to said roller, fixed means for mounting said roller upon a window frame, intermediate the top and bottom thereof, guide means at the sides of the window 95 frame, and releasable means of frictional engagement between said terminal portion and guide means.

5. In an improved window shade, in combination, a spring roller, a shade upon said 100 roller having a stiff, terminal portion, means for moving upper portions of said shade relatively to said roller, fixed means for mounting said roller upon a window frame, intermediate the top and bottom thereof, guide 105 rods for location at opposite sides of said window frame, and slotted members on said terminal portion having loose, canted engagement with said guide rods, the tension of said spring roller, in retracting said 110 shade, thereby tending to straighten said terminal portion, and causing said slotted members to have frictional purchase upon said guide rods.

6. In an improved window shade, in combination, a spring roller carrying a shade, a window frame, means for anchoring the lower end of said shade, vertical guide means at the sides of said window frame, a plain roller slidably engaged with said guide 120 means, and located above said spring roller, whereby the shade may pass over said plain roller and depend below said spring roller, cord and pulley means to actuate said plain roller to move the upper portion of the shade 125 against the tension of the spring roller, and

cord engaging means to secure said upper shade portion in an adjusted position.

7. A window shade comprising a roller, a shade secured at one end thereto and adapted to be wound thereon, means for fixedly mounting said roller intermediate the top and bottom of a window served by said shade, and means for moving a portion of said shade in one direction from said roller, 10 while permitting another portion of said shade to be moved in the opposite direction

from said roller, to partially or wholly obscure or expose upper and lower portions of the window.

Signed at borough of Manhattan in the 15 city, county, and State of New York this 23rd day of October, A. D. 1918.

JUDSON DUNLOP.
